ASH TRAY

Philip J. Schoenberger, 947 Bellows St.,
West St. Paul, Minn.

Filed Jan. 24, 1961, Ser. No. 63,688

Term of patent 14 years

(Cl. D85—2)

FIG. 1

FIG. 2

FIG. 3

FIG. 4

FIG. 5

FIGURE 1 is a perspective view of an ash tray, showing my new design;

FIGURE 2 is a top plan view of the same;

FIGURE 3 is an end elevational view of the same;

FIGURE 4 is a side elevational view of the same; and FIGURE 5 is an end elevational view of the same, showing the end thereof opposite the end shown in FIGURE 3.

I claim:

The ornamental design for an ash tray, as shown.
